UNITED STATES PATENT OFFICE.

CHARLIE BRACKETT BAKER, OF AMORY, MISSISSIPPI.

TOOTHBRAH-HOLDER.

1,397,350.

Specification of Letters Patent. Patented Nov. 15, 1921.

Application filed March 16, 1921. Serial No. 452,701.

To all whom it may concern:

Be it known that I, CHARLIE BRACKETT BAKER, a citizen of the United States, and a resident of Amory, in the county of Monroe and State of Mississippi, have invented 5 certain new and useful Improvements in Toothbrush-Holders, of which the following is a specification.

The present invention relates in general 10 to containers or receptacles, and more particularly to a receptacle especially adapted for use in holding tooth brushes or the like.

The object of the invention is to provide 15 a receptacle of this character which receives the tooth brush and protects the same from contamination by dust, dirt or the like while exposing it to the advantageous action of light, which may be readily sterilized, which provides a separate compartment for each 20 tooth brush, and which is in all respects sanitary and hygienic, which may be readily attached to any convenient support and which is of simple and durable construction, reliable in operation and easy and inexpensive to manufacture.

Other objects and advantages of the invention reside in certain novel features of construction, combination and arrangement of parts which will be hereinafter more 30 fully described and particularly pointed out in the appended claims, reference being had to the accompanying drawings forming part of this specification, and in which:

Figure 1 is a perspective view of the device;

Fig. 2 is a transverse sectional view taken through the spring clips and illustrating their construction; and

Fig. 3 is a similar view, taken through 40 the securing means for the top plate.

Referring to the drawings wherein for the sake of illustration is shown the preferred embodiment of the invention, the numeral 10 designates generally the bracket 45 which is provided with openings 11 by which it may be secured to any suitable support. The bracket is provided at its lower end with a foot plate 12, preferably integral with the plate which constitutes 50 the bracket. Along the outer longitudinal edge of the foot plate a flange 13 is provided and between this flange and the bracket 10 the foot plate is provided with openings 14. Tubes 15 of glass or other suitable transparent material are supported upon the foot

plate and have their lower open ends alined with the openings 14 thereof. The upper ends of the tube are preferably closed. These tubes 15 constitute individual containers or compartments for the tooth 60 brushes. Spring clips 16 secured to the bracket, as at 17, embrace the tubes 15 to releasably secure the tubes against lateral displacement. The clips 16 are preferably of resilient metal and they may be spread 65 to permit of the placing or removing of the receptacles. A top plate 18 abuts the upper closed ends of the tubes and together with the bottom plate prevents longitudinal displacement thereof. The top plate is provided along its outer longitudinal edge with 70 a flange 19, whereby this top plate defines a container for the support of the tooth paste or the like.

In the preferred construction, the bracket 75 plate, the bottom plate and its flange and the top plate and its flange which together constitute the bracket are all constructed from a single blank of metal. The bottom plate and its flange are formed at one end 80 of the blank and the metal at the other end of the blank is bent back upon itself forming an intermediate portion 20, and this intermediate portion 20 is secured flush against the bracket by means of lugs 22 85 struck therefrom and extending through notches 23 provided in the bracket plate 10 and around the bracket plate as clearly shown in Fig. 3. These lugs being carried by the intermediate portion and embracing 90 the bracket plate effect the securing of the intermediate portion flush against the bracket plate. The top plate is then extended at right angles to the bracket plate and the intermediate portion, and its flange 95 19 is extended at right angles to it and in parallelism to the bracket plate.

The openings 14 constitute the entrance to the receptacle and in order to retain the tooth brushes in the receptacle and to prevent ingress of dust or other undesirable matter closures 25 are provided for these openings. These closures 25 comprise swinging plates pivoted at 26 to the foot plate 12 and adapted to be swung to lie across 100 the openings and close the same or to be swung away from the openings so as to leave the same open. The closure plates 25 are provided with thumb pieces 27 whereby they may be readily operated, and these 110

thumb pieces and shoulders 28 also constitute stops for limiting the swinging movement of the closures.

In practice, the receptacle is placed upon any suitable support by means of nails, screws or the like coöperating with the openings 11 of the bracket and the device is then ready for use. It is to be understood that the closed receptacles 15 are first sterilized and are then positioned by spreading the clips 16 and placing the receptacle therein. When the receptacles are carried by the clips they are abutted at their ends by the foot and top plate, respectively and their lower upward ends aline with the opening 14. If the closures 25 are then swung in a counter-clockwise direction access may be had to the interior of the receptacles. The tooth brushes are entered brush-end first through the openings 14 into the receptacle and the lower end of the handle may then be placed upon the closure 25, it being moved sufficiently to accommodate the lower end of the handle. With the lower end of the handle upon the plate 25 the tooth brush is supported in the receptacle during the completion of the closing movement of the plate. When it is desired to remove the tooth brush it is only necessary to swing the plate outwardly with one hand holding the other hand beneath the opening 14. The tooth brush then drops beneath the hole 14. It is obvious that the glass tube provides a dust proof, substantially germ proof receptacle for a tooth brush without depriving them of the cleansing and other advantageous effects of light and without making them inaccessible by children or other persons incapable of manipulating intricate apparatus. It is within the province of any per-

son irrespective of his capacity to insert or remove the brush in the compartments of this receptacle as all that is necessary to effect this is a simple manipulation of the closures 25.

45

I claim:

1. A receptacle of the character described comprising a bracket plate, a foot plate carried by the bracket and having openings therein, a top plate carried by the bracket, tubular containers of glass supported upon said foot plate and abutting the top plate at its upper end, the lower end of said receptacles being open and alined with the opening of the foot plate and the upper ends of said receptacles being closed, spring clips carried by the bracket and embracing the tubular receptacles and swinging closure plates for the openings of the foot plate and pivoted to the under side thereof, said closure plates having thumb pieces whereby they may be manipulated and having limit lugs engageable with the foot plate.

55

2. A receptacle of the character described, comprising a single blank of resilient metal having one end bent to form a foot plate and having its other end bent back upon itself and secured in bent back position and extended at right angles to form a top plate, said foot plate being provided with openings, tubular containers of glass having their upper ends closed and abutting the top plate and having their lower ends open and supported upon the foot plate in alinement with the openings thereof, spring clips for securing the containers against lateral displacement and swinging closure plates pivoted to the underside of the foot plate and adapted to control the openings thereof.
